(57) **CLAIM**

The ornamental design for a communication device for facilitating communication using light radiation, as shown and described.

DESCRIPTION

FIG. 1 is a top front perspective view of a communication device for facilitating communication using light radiation showing my new design;

FIG. 2 is a bottom front perspective view thereof;

FIG. 3 is a top rear perspective view thereof;

FIG. 4 is a bottom rear perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left elevational view thereof; and,

FIG. 10 is a right elevational view thereof.
